(57) **CLAIM**

The ornamental design for an immersion blender, as shown and described.

DESCRIPTION

FIG. 1 is a top perspective view of an immersion blender; FIG. 2 is a front view of the immersion blender; FIG. 3 is a rear view of the immersion blender; FIG. 4 is a right side view of the immersion blender; FIG. 5 is a left side view of the immersion blender; FIG. 6 is a top view of the immersion blender; FIG. 7 is a bottom view of the immersion blender; and, FIG. 8 is a bottom perspective view of the immersion blender.

The broken lines shown throughout the views represent the portions of the immersion blender which form no part of the claimed design.

1 Claim, 5 Drawing Sheets(56)
